UNITED STATES PATENT OFFICE.

HALFDAN A. STEEN, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE.

CIRCUIT-INTERRUPTING APPARATUS.

1,279,781.

Specification of Letters Patent. Patented Sept. 24, 1918.

Application filed July 25, 1914. Serial No. 853,167.

To all whom it may concern:

Be it known that I, HALFDAN A. STEEN, a subject of the King of Norway, residing at Milwaukee, in the county of Milwaukee and State of Wisconsin, have invented a certain new and useful Improvement in Circuit-Interrupting Apparatus, of which the following is a specification.

This invention relates in general to apparatus for interrupting electrical circuits, and has particular relation to such apparatus of the type in which a magnetic field is utilized for extinguishing or suppressing the arc formed on the separation of the contact points.

It is an object of this invention to provide an improved circuit-breaking apparatus capable of quickly and efficiently rupturing the arc formed on the separation of the contacts.

It is a further object of this invention to provide an improved circuit-breaking apparatus wherein a shifting magnetic field is made use of in extinguishing the arc formed between the fixed and movable contacts of the apparatus.

It is a further object of this invention to provide a circuit-breaking apparatus embodying means for establishing an angularly shifting or rotating magnetic field about the points of separation of the contacts of the apparatus and means for controlling the electrical circuits necessary to produce such magnetic field.

These and other objects are attained by this invention, the various novel features of which will appear from the description and drawings, disclosing one embodiment of such invention, and will be particularly pointed out in the claims.

In the accompanying drawings:

Figure 1 is a diagrammatic view of a system comprising a three pole circuit-breaking apparatus embodying this invention.

Fig. 2 is a vertical sectional view of an inclosed circuit-breaking apparatus provided with an arc extinguishing means embodying this invention.

Fig. 3 is a sectional view, looking toward

the bottom of the inclosing receptacle, on 50 the plane of the line 3-3 of Fig. 2.

Fig. 4 is a perspective view showing the relative arrangement of a plurality of electromagnets for producing a shifting magnetic field, and the fixed and movable contacts of the circuit-breaking apparatus, shown in Figs. 2 and 3.

In the embodiment of the invention disclosed in the drawings, an alternating current polyphase generator 5 is connected to 60 a translating device 6, here shown as a motor, through a polyphase transmission line 7, 8, 9. A circuit-breaking apparatus 12 is inserted in the supply circuit of the translating device 6. This circuit-breaking apparatus is shown as comprising a plurality of fixed contacts 13, 14, 15, and a plurality of movable contacts 16, 17, 18, adapted to be moved into and out of engagement with the fixed contacts 13, 14, 15, respectively. 65 The fixed contacts 13, 14, 15, are preferably mounted on a supporting member 19, mounted adjacent to, but separated from, the bottom of an oil-containing receptacle 21.

A part 22 may constitute a frame from 70 which the oil receptacle 21 is suspended, or, where the oil receptacle is fixed in position, the part 22 may constitute a cover for the receptacle. A cap or cover 23 closes a central opening in the part 22. Hollow insulators 25, having a portion extending through the cap or cover 23, are suitably mounted, as by being held in place in a frame portion 24, supported by or integral with the part 22. Contacts 26 are secured 75 in position on the insulator 25 or the frame 24, so as to be adjacent the opening of the insulator. The movable contacts 16, 17, 18, in the form of apparatus shown, are slideable through the insulating bushings 25, engaging, at all times, the respective contacts 26, and are movable into and out of engagement with the fixed contacts 13, 14, 15, respectively. Contacts 26 are connected by flexible connectors 27 to the supply line 7, 8, 9, 80 passing through insulating bushings 28, secured in position in the member 22.

The stationary contacts 13, 14, 15, in the

- form shown, consist of spring cups, split along the sides at 31, as shown in Fig. 2, to provide resilient engaging portions. These fixed contacts are connected to the circuit of the motor or other translating device, through connectors 32, disposed near the bottom of the tank and passing upward along the end of the tank, and through insulating bushings similar to that shown at 28.
- 10 The movable contacts 16, 17, 18, pass through the insulating bushings 25, to the outside of the receptacle where they are connected for simultaneous operation by a frame 35, being suitably insulated therefrom.
- 15 This member 35 is operated to move these contacts into and out of engagement with the fixed contacts 16, 17, 18, respectively, through a toggle 36, one end thereof being connected to the member 35 and the other 20 end to a fixed point at 37. The lower link of the toggle abuts against a stop 38, when the member 35 is in such position that the movable contacts are in engagement with the fixed contacts, the knee of the toggle, at this 25 time, being slightly outside the line joining the two end pivots of the toggle. A spring 39 tends to break the toggle so as to draw the movable contacts out of engagement with the fixed contacts, being prevented from so 30 doing, when in the position shown, by the engagement of the lower link with the stop 38. The toggle is operated through a rod 41, having an elongated slot 42 in which is disposed a pin 43 that passes through the 35 knee of the toggle. The arm 41 is actuated, by a lever 44 pivoted at 45 to a fixed point. A stop 46 is provided for limiting such 40 movement of the lever 44 as causes the separation of the movable contacts from the fixed contacts.
- 40 Mounted on the supports 19 and equally spaced about the fixed contacts 13, 14, 15, are a plurality of electromagnets 51, 52, 53. These magnets are so disposed that their 45 axes coincide at a point approximately in the axis of the fixed and movable contacts, and are supported in position in any suitable manner, being here shown as mounted on supports 54, 55, 56, respectively, which are 50 secured to the supporting member 19, the electromagnets being held in place on the supports by straps 57. The windings of the electromagnets 51, 52, 53, are connected across the three phases of an alternating 55 current supply circuit 61, 62, 63, each magnet being across a separate phase. The connections between the electromagnets and this supply circuit 61, 62, 63, may be through flexible connectors, the conductors of the supply 60 circuit passing into the receptacle through insulators 64 mounted in the part 22 and being disposed adjacent the supports 19.
- 60 The supply circuit 61, 62, 63, is preferably connected to the circuit 7, 8, 9, at a point 65 adjacent the translating device to be controlled, the connection being here shown as made through a transformer 65. In order that energy may not be wasted in the electromagnet windings when no useful work is being done, a switch 70 may be provided for 70 making and breaking the supply circuit 61, 62, 63 for the windings. A spring 71, or other suitable means, may act to hold the switch normally in open position. This switch 70 is provided with an operating 75 spindle 72 adapted to be actuated by a bell crank 73, the same being in turn actuated by the lever 44, through the connecting rod 74.
- 75 The fixed contacts 76 with which the movable contact portions of the switch 70 engage, may be somewhat elongated so as to provide for some movement of the movable contact portions while the same remain in engagement with the fixed contacts. Instead of providing elongated fixed contacts, 80 provision for maintaining contact between the fixed and movable contact portions of this switch may be made by inserting a spring connection between the bell-crank 73 and the operating rod 72, or between two 85 parts of the operating rod 72, or either the fixed or the movable contacts may be of the spring type. The auxiliary switch 70 may be disposed in the same receptacle as the main switch 12, or may be positioned outside 90 this receptacle.
- 90 As shown in Fig. 1, the switch or circuit-breaker is in closed position. To operate the same to open position, the lever 44 is moved in a clockwise direction, the first 100 part of such movement causing the actuation of the switch 70 to closed position, through the connecting rod 74, bell crank 73, and switch spindle 72. When the switch 70 is 105 in closed position, the circuit of the electromagnets 51, 52, 53, is established. It will be obvious that, with this arrangement of electromagnets, a rotating magnetic field is 110 established in the space between the cores of the magnets and adjacent the fixed and movable contacts of the main switch. Continued 115 movement of the lever 44 causes the engagement of the left hand end of the slot 42 with the pin 43, which in the closed position 120 of the switch is located beyond the center line of the toggle. As soon as this pin 43 is moved past the center line of the toggle, the spring 39 acts to suddenly break the toggle and to move the movable contacts 16, 17, 18, out of engagement with the fixed contacts 13, 14, 15. When the pin 43 has moved a sufficient distance beyond the center line to permit the spring 39 to act, the lever 44 125 comes against the stop 46, no further movement of the lever 44 being necessary to accomplish the actual separation of the contacts and the pin 43 merely moving from the left hand end of the slot 42 to the right hand end thereof. Such continued motion of the lever 44 as is necessary to move the pin 43 130

beyond the center line of the toggle and still maintain the movable contacts of the switch 70 in engagement with the fixed contacts thereof is accommodated by the elongated 5 contacts 76.

As the movable contacts separate from the fixed contacts, an arc is drawn. Through the action of the separate magnets carrying out of phase currents, a rotating magnetic 10 field is established about the arc. The action of this field is similar to that of a rotating magnetic field established by the primary of an induction motor, which causes the rotation of the conductors of the secondary member. Hence, the outer portions of the arc are rotated at a high velocity, and, are drawn out so as to assume an approximately spherical outline, this action not only lengthening the filamentary portions of the arc but also 15 spreading the same over a greater area, so that the arc comes into intimate contact with a greater body of insulating fluid. The arc is so drawn and reduced in intensity, through being lengthened and disposed through a 20 larger section of oil, and having the surface thereof exposed to insulating fluid greatly increased, thereby increasing the cooling effect on the arc, that it is soon ruptured. Again, the cooling effect is further height- 25 ened by the action of the rotating arc in putting the oil in motion and drawing it along a circular path so as to bring more oil into contact with the arc and to further distribute the energy to be dissipated. All of 30 these actions contribute to a very quick and efficient rupture of the arc.

It will be obvious that, as soon as the arc is broken, the circuit of the polyphase magnets 51, 52, 53 is also broken, the same being 35 supplied through the contacts 13, 14, 15 and the arcs formed at such contacts. It will thus be apparent that there is no energy expended in the windings of the electromagnets at any time other than when it is de- 40 sired to employ the same for arc rupturing purposes.

As an aid in rupturing the arc, the oil may be given a preliminary movement in a circular or other direction, by mechanical 45 means, as by rotating either the oil receptacle or mechanical elements within such receptacle.

While the embodiment of the invention shown comprises a polyphase magnet for 50 establishing a rotating field, it will be apparent that a single phase magnet may be used with mechanical or electrical means for rotating or shifting the field established.

While the main switch is described as 55 controlling an alternating current circuit, it will be obvious that the invention is equally applicable to apparatus for interrupting direct current circuits, in which case the shifting magnetic field about the contacts would 60 be established from a suitable alternating

current source or from direct current source through a rectifier.

It will be apparent that means other than those shown for making and breaking the circuit of the electromagnets may be used, 70 as for instance, the switch 70 may be operated to closed position by electromagnetic means which are rendered effective prior to actuation of the main movable contacts 16, 17, 18. Again, when the movable contacts 16, 17, 18 are operated by electromagnetic means, a relay may be used for operating the switch 70, which relay is rendered effective a short time prior to the operation 75 of the main contacts.

It should be understood that it is not desired to be limited to the exact details of construction shown and described, for obvious modifications will occur to a person skilled in the art.

It is claimed and desired to secure by Letters Patent:

1. In a circuit-breaking apparatus, relatively movable contacts, and means for establishing about said contacts a magnetic field whose axis is variable as to position.
2. In a circuit-breaking apparatus, relatively movable contacts, and means for establishing an angularly shifting magnetic field about said contacts.
3. In a circuit-breaking apparatus, relatively movable contacts, and means for producing a plurality of de-phased magnetic fluxes about said contacts.
4. In a circuit-breaking apparatus, relatively movable contacts, and means for establishing an angularly shifting magnetic field that cuts the path of separation of said contacts.
5. In a circuit-breaking apparatus, relatively movable contacts, means for accomplishing the separation of said contacts, and means for establishing a rotating magnetic field that tends to rotate parts of an arc drawn between said contacts on separation thereof.
6. In a circuit-breaking apparatus, relatively movable contacts, and a plurality of magnetic flux producing elements disposed about said contacts and adjacent the line of engagement thereof, said elements being capable of producing a rotating magnetic field about said contacts.
7. In a circuit-breaking apparatus, relatively movable contacts, means for accomplishing the separation of said contacts, and means for establishing an angularly shifting magnetic field about said contacts, said latter means being rendered effective by said separating means.
8. In a circuit-breaking apparatus, fixed and movable contacts, means for accomplishing the separation of said contacts, electromagnetic means for establishing an angularly shifting magnetic field about said contacts.

tacts and adjacent the point of engagement thereof, and switch means for rendering said electromagnetic means effective.

9. In a circuit-breaking apparatus, fixed and movable contacts, means for accomplishing the separation of said contacts, means for establishing an angularly shifting magnetic field about said contacts and adjacent the point of engagement thereof, and means for rendering said latter means effective and operated on the actuation of said separating means.

10. In a circuit-breaking apparatus, fixed and movable contacts, means for accomplishing the separation of said contacts, and means for establishing an angularly shifting magnetic field about said contacts and adjacent the point of engagement thereof, said latter means being supplied with energy from a portion of the circuit connected to the contact remote from the source of said circuit.

11. In a circuit-breaker for polyphase circuits, a plurality of fixed and movable contacts, means for actuating said movable contacts, magnetic blow-out means for each set of fixed and movable contacts comprising a plurality of electromagnets disposed about the contacts and adjacent to the line of engagement thereof, said electromagnets being connected across the several phases of said circuit, and means for rendering said magnetic blow-out means effective and subsequently actuating said movable contacts.

12. In a circuit-breaking apparatus, fixed and movable contacts, means for actuating said movable contact, means for establishing a rotating magnetic field about said contacts, switch means for rendering said latter means effective, and actuating mechanism operative for actuating said switch means to render said magnetic field effective and for subsequently actuating said movable contact to open position.

13. In a circuit-breaking apparatus, relatively movable contacts, means for accomplishing the separation of said contacts, means for establishing about the path of separation between said contacts a rotating magnetic field for extinguishing an arc drawn between said contacts on separation thereof, means operative to energize said establishing means, and unitary means for actuating said latter means and for subsequently actuating said separating means.

14. In a circuit-breaker for polyphase circuits, a plurality of fixed and movable contacts, means for actuating said movable contacts, and magnetic blow-out means for each set of fixed and movable contacts comprising an electromagnetic device for establishing a rotating magnetic field about the path of separation of said contacts, the energizing circuit of said electromagnetic device being

connected across a plurality of phases of said polyphase circuit.

15. In a circuit-breaking apparatus, co-operative relatively movable contacts, means operative to cause circuit-rupturing separation of said contacts, and means operative to establish a rotating magnetic field about an arc drawn between said contacts on separation thereof.

16. In a circuit-breaking apparatus, co-operative relatively movable contacts, means operative to cause circuit-rupturing separation of said contacts, and means normally inoperative and operative on the separation of said contacts to establish a rotating magnetic field about an arc drawn between said contacts, said latter means being supplied with energy through the arc formed between said contacts.

17. In a circuit-breaking apparatus, relatively movable and engageable contacts, means operative to cause circuit-rupturing separation of said contacts, and means operative only on actuation of said first means for establishing a rotating magnetic field about an arc drawn between said contacts on separation thereof, said establishing means being supplied with energy through the arc formed between said contacts.

18. In a circuit-breaking apparatus, relatively movable and engageable contacts, electromagnetic means normally inoperative and operative to establish a rotating magnetic field about an arc drawn between said contacts on separation thereof, the energizing circuit of said electromagnetic means being supplied with energy through the arc formed between said contacts, and means operative to successively effectively energize said establishing means and cause circuit-rupturing separation of said contacts.

19. In a multiple circuit-breaker, a plurality of sets of relatively movable and engageable contacts, means for establishing a rotating polyphase magnetic field adjacent the path of separation of the contacts of each set, and instrumentalities operative to successively render said establishing means effective and cause separation of the contacts of each set.

20. In a circuit-breaking apparatus, an oil-containing receptacle, relatively movable and engageable contacts mounted in operative position in the normal oil-containing portion of said receptacle, and means mounted in operative position in said receptacle and effective to produce an angularly shifting magnetic field adjacent an arc formed between said contacts on separation thereof.

21. In a circuit-breaking apparatus, an oil-containing receptacle, relatively movable and engageable contacts mounted in operative position in the normal oil-containing

portion of said receptacle, means normally inoperative and effective to produce a rotating magnetic field adjacent an arc formed between said contacts on separation thereof, and instrumentalities operative to successively render said first means effective to produce the desired magnetic field and cause separation of said contacts.

In testimony whereof, the signature of the inventor is affixed hereto in the presence of two witnesses.
